Primary Examiner — Karen E Kearney*Assistant Examiner* — Kristin E Reed(74) *Attorney, Agent, or Firm* — Knobbe, Martens, Olson & Bear, LLP(57) **CLAIM**

The ornamental design for a portable device, as shown and described.

DESCRIPTION

FIG. 1 is a perspective view of a portable device showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the portable device showing a state in which the device is attachable to and detached from a case to be worn on a wrist;

FIG. 9 is a perspective view of the portable device showing a state in which the device is attachable to and detached from a case to be worn on a neck; and,

FIG. 10 is a perspective view of the portable device showing a state in which the device is attachable to and detached from a case to be held on a waist.
